UNITED STATES PATENT OFFICE.

JEAN MARIE RAYMOND, OF PARIS, FRANCE, ASSIGNOR TO FRANCIS GORDON BATES, OF PHILADELPHIA, PENNSYLVANIA.

COMPOSITION FOR EXTINGUISHING FIRES.

SPECIFICATION forming part of Letters Patent No. 600,802, dated March 15, 1898.

Application filed August 11, 1896. Serial No. 602,432. (No specimens.)

To all whom it may concern:

Be it known that I, JEAN MARIE RAYMOND, chemist, a citizen of the Republic of France, residing in Paris, France, have invented an Improved Composition for Extinguishing Fires, of which the following is a specification.

This invention relates to an improved method of extinguishing fires and a composition therefor.

10 To find the first recorded discovery concerning fireproof substances and fire-extinguishers, it is necessary to revert to Gay-Lussac, who, in 1821, revealed the results of his studies relative to rendering objects uninflammable. Among certain other features the following is of great importance: The combustible gases disengaged by the heat should be mixed in a sufficiently strong proportion with other gases not easily combustible, so as to render the former no longer inflammable. This is the principle which has been followed by those who since that date have invented or discovered liquid chemical preparations which are thrown on a fire for 15 the purpose of extinguishing it. Almost all have decided on the use of volatile incombustible products generating, upon vaporization, carbonic-acid gas, hydrochloric-acid gas, and sulfureted-hydrogen gas, which act on 20 the flame and stifle it.

In certain mixtures for rendering substances fireproof ammoniacal salts are effectively used, which when heated are decomposed into volatile wholly incombustible products 25 and form a mixture of steam and nitrogen as well as gases possessing the property of extinguishing burning substances.

Hitherto solutions of ammoniacal salts of the one part and bicarbonate of soda, combined with sulfuric acid, tartaric acid, &c., of the other part are the only ones which have afforded good results, nitrogen and carbonic-acid gas being recognized as the gases most powerful against fire.

30 Without wishing to dilate more fully upon or to criticise the various other preparations for extinguishing fire, I will point out the incentives and the results of my personal labors.

I have had experience with an apparatus 35 which allows mixing and throwing in any

proportionate quantity any liquid with water under pressure, (forming the subject of United States Patent No. 547,725, dated October 8, 1895,) and being certain of the effective working of this apparatus I consider that the preparation of a powerful extinguisher which could be thrown with water would render signal service in combatting flames, while at the same time increasing the extinctive power of the water, and I have carefully carried out 40 experiments proving the theories which I have established.

Like my predecessors I have considered that I ought to use ammoniacal products; but my choice is more particularly fixed upon two 45 of these salts—ammonium carbonate and ammonium chlorid, which appear to me to be the most efficacious. To these I add anhydrous sodium carbonate and borate of soda. By mixing these substances in different proportions, which I have long studied, and by means of special operations I obtain a solution of great extinguishing power. Used as a ten-per-cent. solution—*i. e.*, ten parts with 50 ninety parts of water—my solution is very effective and rapidly extinguishes fire. However, I wish to go farther, and giving my attention to means for obtaining the immediate extinction of burning light oils and benzins, which has hitherto been impossible in a way 55 other than by the almost impracticable method of suffocating the flame by sand, earth, &c., and for insuring the uninflammability of these oils after their extinction, I have come to the conclusion that the best course 60 to follow to attain these ends is the employment of a composition hereinafter described and claimed and in the manner defined. After repeated and numerous trials I have decided on the instantaneous saponification 65 of these substances, the result of this saponification insuring the extinction of the oils and their subsequent uninflammability. The solution of the problem was not easy, the alkalies not directly saponifying the oils. For 70 this purpose I in the first place determined to use caustic soda. Afterward I worked to make the essences saponifiable by mixing them with a substance possessing this property, so that I might obtain in some degree 75

their subsequent saponification. The substance which has given me the best results is oleic acid, which is first thrown on the inflamed oil, mingles with it, and renders it capable of immediate saponification by the throwing on of a mixture of the above extinguisher with water. Nevertheless I reserve the right to use other substances, such as fatty substances and heavy oils, in which oleic acid predominates.

I have ascertained the following from actual experiment: Four liters of benzin or four liters of mineral oil have been poured by halves into two cement vessels or containers and lighted at the same moment. The combustion of the liquid in one receptacle lasted fully ten minutes, giving forth smoky flames of considerable height. The total extinction of the liquid in the other receptacle was caused by my process, using the before-mentioned patented apparatus and my extinguisher, (solution being of a thirty-five-per-cent. strength,) in fifteen seconds. I afterward tried in vain to relight the liquid so extinguished. It was entirely uninflammable. This interesting result has determined me to publish my process and as a preliminary to protect my invention by this application for patent.

The following is the formula which I generally use, the quantities being slightly variable: water, one thousand parts; borate of soda, forty to sixty; carbonate of soda, (anhydrous) eighty to one hundred and twenty; caustic soda, one hundred and fifty to two hundred; ammonium carbonate, seventy-five to one hundred; ammonium chlorid, two hundred to two hundred and eighty; oleic acid, in any desired quantity, according to the danger which is to be guarded against or the im-

portance or the nature of the fire to be overcome.

The amount of oleic acid employed may vary from ten to twenty-five per cent. of the volume of oil or benzin to be treated.

As an instance of an effective embodiment of my invention I may state that I have added to ten liters of benzin of medium density from two to two and one-half liters of oleic acid, and after intimately mixing the same have thrown onto this mixture the following solution: water, twenty liters; extinguishing compound, before described, three to four liters, with the result that in a few seconds a soft soap was produced which was absolutely uninflammable.

It appears that benzin, petroleum, or derived essences form in the oleic acid added to them a product capable of undergoing saponification, whereas without this addition they are not capable of being saponified.

Having thus described my invention, I claim and desire to secure by Letters Patent—

1. The within-described fire-extinguishing compound, the same consisting of a solution in water of borate and carbonate of soda, and chlorid and carbonate of ammonium.

2. The within-described fire-extinguishing compound, the same consisting of a solution in water of borate and carbonate of soda, caustic soda and ammonium carbonate and chlorid.

In testimony whereof I have signed my name to this specification in the presence of two subscribing witnesses.

JEAN MARIE RAYMOND.
